TRANSMITTER HOUSING OR SIMILAR ARTICLE

Melvin H. Best, Pasadena, and Robert K. Fujioka and Tim M. Uyeda, Los Angeles, Calif., assignors to Hoffman Electronics Corporation, a corporation of California

Filed Oct. 26, 1960, Ser. No. 62,629

Term of patent 14 years

(Cl. D26—5)

FIG. 2.

FIG. 1.

FIG. 3.

FIGURE 1 is a front elevational view of a transmitter housing or similar article, showing our new design,

FIGURE 2 is a top plan view thereof, and

FIGURE 3 is a side elevational view thereof.

The rear of the housing is plain and unornamented.

The essential features of our design reside in those portions shown in full lines.

We claim:

The ornamental design for a transmitter housing or similar article, substantially as shown and described.
